(57) **CLAIM**

The ornamental design for an insulated pint, as shown and described.

DESCRIPTION

FIG. 1. is a top perspective view of an insulated pint according to the present invention.

FIG. 2 is a side view of the insulated pint of FIG. 1.

FIG. 3 is a top plan view of the insulated pint of FIG. 1; and, FIG. 4 is a bottom plan view of the insulated pint of FIG. 1. The broken lines in the drawings represent unclaimed subject matter and form no part of the claim.
